MOP SQUEEZING DEVICE

Edward Pavek, Minneapolis, Minn.

Application June 27, 1932. Serial No. 619,390

24 Claims. (Cl. 15—261)

This invention relates to a mop wringing device, and while the invention may have various applications, it particularly is designed as a mop wringing device adapted to be carried by a pail

5 in which the wash water or rinsing water for the mop is carried. While various mop wringing devices have been proposed, it has heretofore usually been necessary for the operator to operate either a manual or pedal lever for squeezing the mop.

10 In the particular type of mop wringer or squeezer illustrated, it has usually been the practice to provide a lever located quite close to the pail for moving the mop squeezing elements together. This necessitated the operator stooping over and

15 usually getting his face more or less directly over the hot water in the pail. Such an operation is tiring and unpleasant.

It is an object of this invention, therefore, to provide a mop wringing or squeezing device comprising members movable towards each other, together with means adapted to be engaged by the handle of the mop so that it is merely necessary to swing the handle of the mop with the mop between said members, to squeeze the mop. The handle can be easily swung without the operator having to bend over very far.

It is a further object of the invention to provide a mop wringing or squeezing device adapted to be used with a pail and comprising a frame, 30 a pair of swinging plates movable toward and from each other carried on said frame, one of said plates having an upwardly extending portion with means adapted to be engaged by the mop handle whereby a handle equipped mop can be placed between said plates, the handle engaged with said means, and said handle and plates moved to squeeze the mop.

It is still another object of the invention to provide a mop wringing or mop squeezing device 40 comprising a frame adapted to be supported by a pail, a pair of revolvably movable members or plates mounted in said frame, a roller engaging one of said plates for moving the same, said roller preferably being adjustable to vary the movement of said plate, together with means for moving the other plate to cause approaching movement of said plates.

It is still another object of the invention to provide a mop wringing device comprising a swinging plate and a device of novel form carried by said plate adapted to be engaged by the mop handle to be moved thereby to swing said plate.

These and other objects and advantages of the invention will be fully set forth in the following description made in connection with the accom-

panying drawings, in which like reference characters refer to similar parts throughout the several views, and in which:

Fig. 1 is a view in side elevation of a mop wringing device embodying the invention, a pail 60 being shown partly in section;

Fig. 2 is a vertical section taken on line 2—2 of Fig. 1, as indicated by the arrows;

Fig. 3 is a vertical section taken on line 3—3 of Fig. 2, as indicated by the arrows, certain 65 parts being shown in different position in dotted lines;

Fig. 4 is a transverse section taken on line 4—4 of Fig. 3, as indicated by the arrows;

Fig. 5 is a perspective view shown on an en- 70 larged scale, of the handle engaging member;

Fig. 6 is a view in side elevation of a modified form of the invention;

Fig. 7 is a view similar to Fig. 3 showing said modified form;

Fig. 8 is a horizontal section taken on line 8—8 of Fig. 6, as indicated by the arrows; and

Fig. 9 is a partial view similar to Fig. 6, showing a further modification.

Referring to the drawings, a pail 10 is shown 80 of substantially cylindrical form having a slight flare towards its upper end and equipped with a bead at its upper end. A mop wringing device is shown comprising a frame designated generally as 11, said frame comprising parallel side mem- 85 bers 11a connected at their bottoms by a portion 11b thus forming a substantially U-shaped frame. Members 11a have plates 12 riveted thereto and extending parallel thereto, said plates having downwardly extending portions 12a forming 90 in effect hooks adapted to extend over the top edge of the pail 10 at spaced points to support the frame 11. The side members 11a are apertured at their upper ends to receive a rod 13 extending therebetween, the same having a cot- 95 ter pin 14 extending therethrough at one end at the outer side of one of said side plates and having its end bent downwardly and then inwardly substantially at right angles at its other end forming the portion 13a. Portion 13a is 100 adapted to engage with the edge of a plate 15 secured to one of the plates 12. A bolt 16 ex- tends through plates 12 and 15 and through a slot 15a in the plate 15 and is threaded at its outer end to be engaged by a thumb nut 17. Plate 15 105 can thus be moved upwardly and downwardly and held in different positions by tightening the thumb nut 17. The member 13a will thus be held in different positions according to the position of plate 15. A member designated generally 110

as 18 is traversed by the pivot rod 13 and swingable about the axis of said rod. Said member 18 comprises a rear plate 18a and side plates 18b extending forwardly therefrom substantially at right angles. The side plates 18b are substantially of sector-shape, having curved upper ends which are bent slightly outwardly. A pair of angle bars 19 are secured to the rear of plate 18a, which plate extends upwardly in substantially triangular form, said angle bars being secured in any suitable manner as by the rivets shown. Bars 19 extend above plate 18a in slightly spaced relation and a flat bar 20 is secured between bars 19 and extends thereabove, the same having secured thereto a plate 21 which has a narrow strip at one end, one portion of which fits alongside of bar 20 and is apertured to have pass therethrough a screw 22 secured in the bar 20 and have a head countersunk in said bar. Screw 22 is equipped with a nut 23 and a compression coil spring 24 surrounds said screw and is disposed between said nut and plate 21. Plate 21 has an end portion 21a extending outwardly and curved laterally from bar 20 and said plate has a much wider portion 21b curved into substantially semi-cylindrical shape to form a hook. Portion 21b has its concave portion covered with a soft leather member 25, the edges of which are folded over the edges of portion 21b and held in place at the outer side of said portion by the lacing 26. The free edge of the semi-cylindrical portion of member 21 extends in an inclined direction so that the opening at the side thereof is wider at the lower end than at the upper end. The plates 18b have a reinforcing strip 18c extending across the front thereof at their upper inner portions, the ends of said strip extending across the plates 18b at their outer sides and being riveted thereto. A plate 27 is provided, adapted to extend between the plates 18b, said plate being slightly curved in a compound curve as shown in Figs. 1 and 3. Said plate is bent at an angle adjacent one end and has an eyelet formed at its lower end traversed by a pivot pin 28 which extends through and between plates 18b, being held therein by being headed at one end and having a cotter pin 28a extending therethrough at its other end. A torsion spring 29 is disposed at each end of the pivot pin 28 surrounding the same and having one end bearing against plate 27 and its other end bearing against plate 18a in the corner between the latter and side plates 18b. These springs tend to keep plate 27 moved away from plate 18a and moved against strip 18c. Bars 30 are pivoted by the headed rivets 31 at their lower ends to the side members 11a, said bars extending upwardly and having extending therebetween and secured therein the headed pin 31 having collars 32 thereon between the ends thereof and between the same and bars 30 are disposed rollers 33. These rollers engage the outer side of plate 27 and act in the operation of the device to move said plate toward plate 18a. Bars 30 are bent slightly intermediate their ends and just below said bends they are disposed alongside of the plates 12b secured to and extending inwardly from said members 11a, said plates being shown as forming part of the plates 12. The plates or portions 12b have a plurality of holes 12c therethrough and headed and nutted bolts 34 pass through one of these holes and the bars 30 so that said bars and hence the rollers 33 can be held in different positions. A drain pan 35 is secured to side members 11a, the same having a narrow flange extending about its sides and

rear end and having a bottom inclining downwardly into the pail 10. Plate 27 is provided with a plurality of holes 27a and said plates 18b are provided with a plurality of holes 18d, these holes being provided for the passage of the water when the mop is squeezed. 80

In operation the device will normally occupy the position shown in Figs. 1 and 2. The wash water will be placed in the pail 10 and when it is desired to rinse and squeeze the mop, the wet mop will be placed in the pocket formed by plates 18a, 18b and 27, which pocket, as clearly shown in the drawings is the shape of a sector of a cylinder. The mop is placed in said pocket and the operator then moves the handle 36, shown in dotted lines in Figs. 1, 2 and 3 into the portion 21b of plate 21, the same moving between the end of said portion and the portion 21a. The handle is then engaged in the semi-cylindrical portion 21b and swung forwardly transversely of the pail 10. The opening in member 21 being wider at the bottom facilitates the entry and exit of the mop stick. When the handle exerts pressure on portion 21b it pivots on the bolt 22 and swings into the position shown in dotted lines in Fig. 4, 90 so that it is directly in front of bar 20. The operator now merely swings the mop handle forwardly and plate 18a is moved to the left as seen in Figs. 1 and 3, plates 18b moving at the side of plate 27. Plate 27 is engaged by the rollers 33 105 and as plate 18a swings toward the left, the rollers move upwardly on plate 27 and it is moved toward plate 18a. The mop is thus squeezed between plate 27 and plate 18a. The water squeezed from the mop passes through the holes 18d and 27a and also runs down between plates 18a and 27 into the drain pan 35 from which it runs down into the pail 10. It will thus be seen that the operator can squeeze the mop without bending down low over the bucket of hot water. All that 115 is necessary is merely to hold the mop handle at a point high above the bucket and swing the handle forwardly over the bucket. When the handle is swung back, the springs 29 again move plate 27 to its normal position and the mop can 120 be lifted from between plates 18a and 27. The rollers 33 can be located in different positions by placing the bolts 34 in different holes 12c. This causes a difference in the distance the plates 18a and 27 are spaced and also varies the leverage 125 exerted on plate 27 in squeezing the mop. By moving the plate 15, the portion 13a of the pivot 13 is stopped in a different position and this results in the member 19 being held in a more nearly vertical position. This adjustment is provided so that member 19 will not extend at too great an angle to the vertical so as to accommodate buckets with different degrees of flare and to suit various operators. 130

In Figs. 6, 7 and 8 a modified form of construction is shown. In this form a frame 40 is provided having side members 40a extending downwardly into the bucket and connected by a lower bar 40b. Portions 40a and 40b are shown as bent from a single bar and riveted at the upper 140 ends of bars 40a to the upper part of frame 40. Frame 40 also comprises side plates 40c of general sector shape, the same having rearwardly extending projections 39 forming hooks adapted to extend over the rim of the pail 10. A pivot member 41 extends through and between plates 40c, the same being headed at one end and held in place at its other end by the cotter pin 42. A member 43, comprising a plate 43a, is provided, the same also comprising a pair of angle bars 43b 150

secured to the back of the plate 43a. Pivot 41 extends through the bars 43b so that member 43 is pivoted to the plates 40c and swingable about the axis of pivot 41. The angle bars 43b extend 5 beyond the upper end of plate 43a, which plate is of the general shape of plate 18a already described, said bars being in spaced relation above said plate. The bar 20 already described having member 21 carried thereby, is secured between 10 the upper ends of bars 43b as described in connection with Figs. 1 to 3. A pivot 44 extends through the bars 43b below the pivot 41 and a plate 45 is provided of a width to move between plates 40c, the same being slightly curved in a 15 compound curve and having its lower end bent at an angle and provided with an eyelet through which pivot member 44 passes. Pin 44 is headed at its ends to be retained in the bar 43b. The plates 40c as shown have curved tops, the edges 20 of which are bent slightly outwardly, and said plates have formed therein a plurality of apertures 40d shown as rectangular slots arranged in two rows. Bars 46 are provided extending along the outer sides of plates 40c and having inturned 25 ends 46a adapted to be received in one of the slots 40d. Bars 46 are bent transversely and then inwardly substantially ninety degrees, the inwardly extending portions 46b having secured therein a headed pin 47 having spaced collars 48 thereon. Rollers 49 are journaled on pin 47 between collars 48 and the members 46b respectively, and said rollers are disposed to engage the outer side of the plate 45. Plates 40c have holes 49c therein at the inner ends of the rows of slots 30 40d and bolts 50 extend through holes 49c and through holes in the bars 46, said bolts having heads countersunk in the plates 40c and being equipped with nuts at the outer sides of bars 46. Frame 40 has a drain pan 51 secured thereto beneath plates 43a and 45, the same having a narrow flange about its sides and rear end and having a bottom sloping downwardly into the pail 10. Torsion springs 52 extend about the ends of pin 44 and have one end engaging plate 43a and 45 another end engaging plate 45, said springs acting to move plate 45 away from plate 43a. The plates 40c are provided with drain holes 40f and plate 45 is provided with drain openings 45a. In operation, when it is desired to squeeze the 50 mop, the same is placed between the plates 45 and 43a and between the side plates 40c. These plates define a recess shaped substantially in the form of the sector of a cylinder. The operator then moves the handle into the hook portion of plate 21 and swings the handle forwardly transversely of the pail 10. The handle moves plate 21 and member 43 forwardly as indicated in Fig. 7 and as said member moves forwardly, plate 45 is moved against the rollers 33, said rollers moving upwardly along plate 45 so that said plate is also moved toward the plate 43. The mop is squeezed between the plates 43a and 45, the water from the mop draining through 55 holes 40f and 45a and running down between plates 45 and 43a into the pan 51 from which it drains into pail 10. The bars 56 can be moved to have their portions 46a extend into different slots 40d and the position of the rollers 49 is thus changed. The rollers can be moved either inwardly to cause a closer approach of plates 43a and 45, or the rollers can be moved upwardly, giving more leverage in the movement of the plate 45. When the mop handle and member 43 are moved upwardly and rearwardly from over 60 the pail 10, springs 52 move plate 45 to normal

position and the mop can be lifted from between plates 45 and 43a.

In Fig. 9 the structure is the same as shown and described in connection with Figs. 6, 7 and 8, except that in place of having the slots 40d and the bars 46, holes 40g are provided. Several pairs of said holes are shown disposed at different distances vertically of said plates 40c and also disposed different distances from the edge of said plate. A pivot bolt 54 is adapted to pass through holes 40c and to carry rollers 55 engaging plate 45. Pivot bolt 54 will have a head at one end and be held at its other end by a cotter pin. By disposing the pivot bolt 54 in the different holes, the position of the rollers 55 engaging plate 45 can be changed.

From the above description it is seen that applicant has provided a mop wringer which is simple in construction and which is very easily and conveniently operated. It is not necessary for the operator to bend low over a bucket of hot or steaming water and the inconvenience of bending down over the bucket and also the unpleasant contact with the steam from the water, are avoided. The handle of the mop is easily 100 and quickly engaged with the member 21 and as above described, it is only necessary to swing the handle of the mop forwardly over the pail to effect the squeezing or wringing operation. The mop handle being moved towards and over 105 the pail there is no tendency to upset the pail. The mop is effectively squeezed or freed of water and the water drains quickly back into the pail. The device is easily and quickly placed in operative position on the pail. The parts are few and 110 the structure is quite rugged. Sufficient flexibility is provided to give the desired operating conditions and to suit the mop being used. The device has been amply demonstrated in actual practice and found to be very successful and 115 efficient.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:—

1. A mop wringer having in combination, a frame adapted to be supported on a pail, a mop squeezing means carried by said frame, means for operating said means including a member extending upwardly above said frame, a bar secured 120 to said member and extending upwardly therefrom, a plate bent intermediate its ends to extend about said bar and have its end portions directed forwardly of said bar, one of said portions being reversely bent to form a hook adapted to 125 embrace a mop handle and the other portion extending at one side of said hook forming therewith a passage through which said handle must pass to engage said hook.

2. A mop wringer having in combination, a frame adapted to be supported on a pail, a mop squeezing means carried by said frame, means for operating said means including a member extending upwardly above said frame, a bar secured 130 to said member and extending upwardly therefrom, a bolt secured in said bar extending transversely thereof, a plate bent to embrace said bar and having a portion thereof extending along the side of said bar and apertured to have said bolt pass therethrough, a spring disposed on said bolt 135

and acting to normally hold said portion against said bar, said plate having another portion extending forwardly at an angle at the other side of said bar and shaped at its outer end to form 5 a hook adapted to be engaged by the handle of the mop with the mop portion disposed in said mop squeezing means whereby said mop handle can be engaged in said hook and said plate swung to bring said latter portion substantially parallel to the side of said bar with said hook directly in front of said bar.

3. The structure set forth in claim 2, said portion of said plate extending alongside of said bar and apertured to receive said bolt, also extending forwardly of said bar and disposed at 15 one side of said hook forming with said hook a passage through which said handle must pass to be engaged in said hook.

4. A mop wringer having in combination, a 20 frame adapted to be supported on a pail, a mop squeezing means carried by said frame, means for operating said means including a member extending upwardly above said frame, a bar secured to said member and extending upwardly therefrom, a plate shaped to form a hook secured 25 to said bar and a layer of flexible soft material covering said hook, and means for holding said flexible material in place.

5. A mop wringer having in combination, a 30 frame adapted to be disposed in a pail and having means engaging the pail to support said frame, a member having a plate extending transversely of said pail pivoted to said frame, a second member having a plate extending transversely of said pail pivotally mounted to move toward and from said first mentioned plate, means for causing approaching movements of said plates when one of them is swung, one of said members having an upwardly extending portion secured thereto and swingable therewith, means 35 on said portion adapted to receive a mop handle whereby the mop may be placed between said plates, the handle engaged by said last mentioned means and said member carrying said means swung to move said plates together and squeeze said mop.

6. A mop wringer having in combination, a 40 frame adapted to be disposed in a pail and having means engaging said pail to support said frame, said frame having parallel portions, a member disposed between said portions and pivoted to said frame, a second member comprising a plate pivoted adjacent its lower portion to said member and normally diverging therefrom, a 45 roller engaging said last mentioned member to move the same toward said first mentioned member when said latter member is swung, said first mentioned member having an upwardly extending portion, a hook on said portion for embracing a mop handle whereby a mop handle can be 50 engaged in said hook, and said member swung to cause said plates to approach each other.

7. The structure set forth in claim 6, said 55 roller being movable to different positions to cause the plate engaged thereby to approach said other plate with a quicker movement when said other plate is swung.

8. A mop wringer having in combination, a 60 frame having parallel sides and hooks projecting therefrom adapted to engage over the side of the pail, a pivot rod extending between said sides, a member pivoted on said rod swingable transversely of said pail and having a plate extending 65 between said sides, a second member pivoted adjacent its bottom to said member and disposed

opposite the said plate, and a roller mounted on said frame and engaging said last mentioned plate to cause movement thereof towards said first mentioned plate when said first mentioned member is swung toward said second mentioned member.

9. The structure set forth in claim 8, said first mentioned member having means extending upwardly and constructed and arranged to receive a mop handle so that said member can be swung 85 thereby.

10. A mop wringer having in combination, a 90 frame having side portions, a member having side plates, and a plate extending between the same pivoted on said frame, a second member movable between said side plates and opposing said last mentioned plate and pivoted to said first mentioned member, said plates forming a pocket to receive a mop, said first mentioned member having an upwardly extending portion, the member carried by said portion adapted to embrace a mop stick whereby said first mentioned member can be swung to cause approaching 95 movement of said plates.

11. A mop wringer having in combination, a 100 frame adapted to be supported by a pail and having spaced parallel side plates, a member pivoted to said frame and having a plate extending between said side plates, a second member comprising a plate disposed between said side 105 plates and pivoted adjacent its bottom to said first mentioned member, a roller engaging said last mentioned member at the side opposite said first mentioned member, a hook carried by said first mentioned member whereby a mop can be 110 placed between said plates, the handle of said mop engaged in said hook, and said first mentioned member swung toward said second member to cause approaching movement of said plates and squeeze said mop.

12. A mop wringer having in combination, a 115 frame having means to engage over the edge of the pail and be supported thereon and having side portions, a plate pivotally mounted on said side portions and extending therebetween, 120 a second plate swingingly connected to said plate adjacent the bottom thereof and facing said first mentioned plate, means for swinging said first mentioned plate relatively to said frame toward said second mentioned plate, and means 125 engaging said second mentioned plate to simultaneously move it toward said first mentioned plate.

13. A mop wringer having in combination, a 130 frame having means to engage a pail and be supported thereon, a plate pivoted to said frame, a second plate pivoted to said first mentioned plate, means for swinging said first mentioned plate inwardly of said pail, and means for simultaneously swinging said second mentioned 135 plate toward said first mentioned plate.

14. A mop wringer having in combination, a 140 frame adapted to be supported on a pail, a mop squeezing means carried by said frame, means for operating said means including a member extending upwardly above said frame, a bar secured to said member and extending upwardly therefrom, a metal plate shaped to form a hook secured to said bar, a member of soft material carried by said hook, and means for holding said 145 last mentioned member in place.

15. A mop wringer having in combination, a 150 frame adapted to be supported on a pail, a pair of plates mounted in said frame adapted to move toward and from each other and adapted

- to have a mop placed therebetween to be squeezed thereby, one of said plates having a member extending upwardly therefrom, a second member mounted on said last mentioned member and extending laterally therefrom adapted to receive the stick of a mop when the mop is placed between said plates, whereby said stick can be swung to move said members and said plate, said second member being movable transversely of said first mentioned member. 5
16. The structure set forth in claim 15, and resilient means engaging said last mentioned member against which it is moved when moved transversely of said first mentioned member and adapted to restore it to normal position. 10
17. A mop wringer having in combination, a frame, a plate pivotally mounted in said frame for swinging movement relatively thereto, a second plate pivotally connected to said first mentioned plate, means for swinging said first mentioned plate toward said second plate, means engaging said second plate at the side thereof opposite said first mentioned plate and over which said second plate is moved by the swinging movement of said first mentioned plate for resisting movement of said second plate and assisting in causing approaching movement of said plates. 15
18. A mop wringer having in combination, a frame, a plate pivotally mounted in said frame for swinging movement relatively thereto, a second plate pivotally connected to said first mentioned plate, means for swinging said first mentioned plate toward said second plate, and a roller engaging said second plate and resisting movement thereof away from said first mentioned plate and over which said second plate is moved by the movement of said first mentioned plate for assisting in the closing movement of said plates to squeeze a mop therebetween. 20
19. A mop wringer having in combination, a frame adapted to be disposed in a pail and having means extending over the edge of said pail to support said frame, a member carried by said frame having side portions and a transverse plate extending therebetween, a second plate opposed to said first mentioned plate, said plates being swingable about an axis adjacent the lower ends for approaching and receding movement, means engaging the side of said last mentioned plate opposite said first mentioned plate over which said last mentioned plate is moved by swinging movement of said first mentioned plate, said first mentioned plate having an upwardly extending portion secured thereto and
- movable therewith, a means on said portion adapted to be engaged by a mop handle whereby a handle-equipped mop may be placed between said plates, the handle engaged by said last mentioned means and said handle swung to move said plates toward each other and squeeze said mop. 25
20. A mop wringer having in combination, a frame, a plate pivotally mounted on said frame for swinging movement relatively thereto, a second plate pivotally connected to said plate adjacent the bottom thereof and facing the same, means for swinging said first mentioned plate toward said second plate and simultaneously swinging said second plate, means engaging said second plate at the side thereof opposite said first mentioned plate to resist movement of said plate away from said first mentioned plate, said second plate moving relatively to said means so that said means is progressively a greater distance from the connection between said plates in the swinging and approaching movement of said plates. 30
21. A mop wringer having in combination, a frame, a mop squeezing means carried by said frame, means for operating said means including a bar extending upwardly above said frame, a plate secured to said bar having the form of a semi-cylinder, said plate and semi-cylinder having an opening at one side and having a free edge inclined to an element of said semi-cylinder whereby said opening is larger at its bottom than at its top. 35
22. A mop wringer having in combination, a frame adapted to be supported in a pail, a plate pivotally mounted in said frame for swinging movement relatively thereto, a second plate pivoted adjacent its bottom to said first mentioned plate and means extending upwardly from said first mentioned plate for swinging it toward said second plate and for simultaneously swinging said second plate in the same general direction as said first mentioned plate is swung to cause approaching movement of said plates. 40
23. The structure set forth in claim 19 and means on said frame for varying the initial position of said first mentioned plate and upwardly extending portion thereof relatively to the vertical. 45
24. The structure set forth in claim 17, and means for varying the initial position of said second mentioned means whereby the positions of said plates in mop squeezing position may be varied. 50
